(57) **CLAIM**

The ornamental design for a storage bin, as shown and described.

DESCRIPTION

FIG. 1 is a top front perspective view of a storage bin, showing my new design.

FIG. 2 is a bottom rear perspective view of the storage bin.

FIG. 3 is a front elevational view of the storage bin.

FIG. 4 is a rear elevational view of the storage bin.

FIG. 5 is a left side elevational view of the storage bin.

FIG. 6 is a right side elevational view of the storage bin.

FIG. 7 is a top plan view of the storage bin; and,

FIG. 8 is a bottom plan view of the storage bin.

The storage bin is shown with a symbolic break in its length, and two symbolic breaks in its width. The appearance of any portion of the article between the break lines forms no part of the claimed design.

1 Claim, 8 Drawing Sheets
